(57) **CLAIM**

The ornamental design for an articulating arm assembly, as shown and described.

DESCRIPTION

FIG. 1 is a top-perspective view of an articulating arm assembly;

FIG. 2 is a front view thereof;

FIG. 3 is a back view thereof;

FIG. 4 is a right-side view thereof;

FIG. 5 is a left-side view thereof;

FIG. 6 is a top view thereof; and

FIG. 7 is a bottom view thereof.

FIG. 8 is a top-perspective view of the first embodiment of an articulating arm assembly, shown in a collapsed state;

FIG. 9 is a front view thereof;

FIG. 10 is a back view thereof;

FIG. 11 is a right-side view thereof;

FIG. 12 is a left-side view thereof;

FIG. 13 is a top view thereof; and

FIG. 14 is a bottom view thereof.

The broken lines shown in the drawings are for illustrative purposes only and form no part of the claimed design.
